UNITED STATES PATENT OFFICE.

WILLIAM KLINE AND JULIUS C. JADICKE, OF WILMINGTON, DELAWARE.

COMBINED SQUARE, CALIPERS, AND DIVIDERS.

SPECIFICATION forming part of Letters Patent No. 357,487, dated February 8, 1887.

Application filed July 29, 1886. Serial No. 209,430. (No model.)

To all whom it may concern:

Be it known that we, WILLIAM KLINE, a native of Hungary and a subject of the Emperor of Austria-Hungary, and JULIUS C. JADICKE, a native of Russia and a subject of the Czar, both residing at Wilmington, in the county of New Castle and State of Delaware, have invented certain new and useful Improvements in Measuring-Instruments; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention relates to certain new and useful improvements in measuring-instruments, the object of the same being to provide a measuring device which consists of a pair of compasses, a pair of inside and outside calipers, and a straight-edge or rule which may be folded so as to form a square, the parts being organized so that they may be folded parallel with each other, so as to provide a convenient pocket implement, as will be hereinafter fully set forth.

In the accompanying drawings, which illustrate our invention, Figure 1 is a perspective view of our improved implement, showing the parts opened, so as to better illustrate our invention. Fig. 2 is a plan view, which shows the straight-edge adjusted so as to form a try-square, and Fig. 3 is a side view showing the parts folded upon each other. Fig. 4 is a sectional view taken on line $x-x$ of Fig. 3.

A A' refer to the members of the straight-edge or rule, which are secured to each other by a pivot, a , said pivot also securing the legs of the compasses and calipers to each other and to the members of the straight-edge. The member A of the straight-edge is provided with an upwardly-projecting pin or stop, b , which is located near one corner of the same, adjacent to the pivot-pin a . The member A' is provided with a circular end, c , and at one side thereof with a curved recess, d , against which said pin or stop will abut when the parts are adjusted upon each other, as shown in Fig. 2. Said groove or recess d and the stop b provide a means whereby the members A and A' will be located at right angles with each other when

it is desired to form a try-square. The opposite side of the member A' is provided with an open slot, e , the base of which will be on a line with one side of the pivot-pin a and with the lower edge of the member A, so that when the member A is turned upon the pivot-pin a so as to lie parallel with the member A said open slot e will engage with a pin or stop, b , so as to maintain one or both edges of the parts A and A' rigidly in alignment with each other, and thus form a straight-edge. One of the sides of the members A and A' is provided with a scale representing inches.

B B refer to the legs of the pair of compasses, the upper portion of one of the legs being recessed, so that the upper portion of the adjacent member will lie within the same, as is usual in the construction of such instruments. These compasses lie adjacent to the member A' of the rule or try-square. Next to the compasses B B and upon the pivot-pin a are secured the legs C C of the calipers. The upper portion of these legs adjacent to the pivot-pin a lie one upon each other, so that they can be turned completely around or reversed, and the legs are bent or curved only at their extreme outer ends, as shown at f , in order that they may be employed either as inside or outside calipers.

If desirable, the pivot a may be screw-threaded at one end and provided with a thumb or set screw for locking the parts in a desired position.

We claim—

1. In a measuring-instrument, the combination of the rules A and A', pivoted together at one end, one of said rules being provided with a stop adjacent to the pivot, the pivoted end of the other rule being rounded in a three-quarter circle terminating in a recess, d , and slot e , whereby the rules may be folded upon each other, or locked at right angles with each other, or extended and locked with their respective edges in alignment, substantially as described.

2. In a combined measuring-instrument, the combination of the rules A A', the dividers B, the calipers C, and the pivot-bolt, said parts being constructed and arranged as described, whereby the dividers and calipers may be turned a complete revolution upon said bolt.

3. As a new article of manufacture, a com-

combined measuring-instrument consisting of rule A, having a stop-pin, rule A', having a curve at its end terminating in a recess, d, and slot e, the dividers, the calipers, and a threaded pivot-bolt connecting the parts together and to each other, and to lock them in different positions of adjustment, substantially as described.

In testimony whereof we affix our signatures in presence of two witnesses.

WILLIAM KLINE
JULIUS C. JADICKE
